UNITED STATES PATENT OFFICE.

EDOUARD BELIN, OF PARIS, FRANCE.

TACHYTELEGRAPH AND TELETYPE MACHINE.

1,175,685.

Specification of Letters Patent.

Patented Mar. 14, 1916.

Application filed April 25, 1911. Serial No. 623,328.

To all whom it may concern:

Be it known that I, EDOUARD BELIN, a citizen of the Republic of France, residing at Paris, in the Republic of France, have invented certain new and useful Improvements in Tachytelegraph and Teletype Machines, of which the following is a specification.

The present invention relates to a method 10 of transmitting signals for tachytelegraph and teletype systems. A tachytelegraph system will be understood to imply a high speed telegraph system, while a teletype system is a telegraphic system for the transmission of typed messages.

Among the requirements set up by the continual progress in the methods of the daily press, one of the most important is that of rapid composition of matter from a 20 distance for foreign or provincial editions of a newspaper which is printed in a capital, or some other large center. Numerous attempts have been made to comply with this requirement by various inventors, but up to 25 the present no practical solution has yet come into use because none are exempt from certain defects which render the use of the invention too slow or too complicated, or both.

Now the primary object of the present invention is to provide a method and apparatus such that a stereotype of a typographic composition may be very readily made at a distance. Also the stereotype received must 35 be a true copy of that sent, the cost must be reduced to the minimum, and the transmitting line must be appropriated for the smallest possible time, and the operation of the apparatus must not require supplementary work or special skill. The same principles and similar arrangements enable an 40 ordinary telegraphic apparatus to be adapted for a maximum rate of operation and output, and adapted to record messages photographically in roman or any other characters desired. In both systems the correction or adjustment of the text is possible on a perforated transmitting tape or band.

Broadly defined the invention consists of 50 automatic transmission by means of a perforated band or tape, the idea of which is already known, but under special conditions which are of the greatest importance to insure rapid working.

In all telegraphic apparatus each letter 55 is represented by a series of successive impulses and the different letters and characters are distinguished from each other by different combinations of positive or negative, short or long signals. In most automatic systems these impulses are derived from either a series of perforations on the tape or a series of contacts arranged in succession to one another. In certain of these systems like Bain's telegraph or the Pollak 60 Virag telegraph, the perforations are variable in length. In others the number of perforations is greater for long signals than for short and an electrical arrangement at the receiver operates to combine a number of 65 closely-spaced impulses into a single one. Such arrangements however have the very serious disadvantages of necessitating a considerable linear displacement of the tape for 70 each character sent and of blocking the line 75 for each character sent during the time necessary to send several impulses. The first of these disadvantages is avoided in the Baudot automatic apparatus in which the movement of the keyboard is controlled by a 80 series of perforations upon a single straight line at right-angles to the direction of motion of the tape, but the second disadvantage is also present in this apparatus.

The present invention is designed to produce an apparatus which requires for any character only a single impulse of current and an amount of displacement of the tape corresponding to the width of a single perforation. Hitherto these automatic apparatus have required a special machine for the perforation of the tape or band. The present invention however, provides a machine in which the tape or band is perforated either directly by the action of the keyboard 90 of the composing machine as fast as the composition is carried out, or by means of a machine resembling the ordinary typewriter. It is this feature which enables the text represented by the perforations to be 95 corrected either upon the tape itself, or upon a detachable block or counterfoil.

The present invention further produces a machine in which each of the characters is transmitted by means of a single signal, each 100 signal being of the same duration so that distinction is made between them by the strength of the current impulses. The strengths of

the current selected are those in common use in telegraphy. They are always great enough to obviate the effect of eddy currents, earth currents, and the effects of mutual and self-induction.

The present invention also produces combinations of mounting as hereinafter set forth in order to avoid complexity in the perforating and transmitting members, and in order not to give the tape too great a width. The satisfactory working of an apparatus based on the strengths of the current impulses, requires in addition to an extra resistance at the extremity of the line, an automatic arrangement for regulating the resistance of this line. A suitable arrangement is set out in my Patent No. 1,058,533, filed on the 20th December 1911.

The method of construction and of operation of the improved system is described in connection with the accompanying drawings in which—

Figure 1 is a plan and Fig. 2 an end elevation of the transmitting apparatus. Fig. 25 3 is a diagrammatic plan view of the receiver as a whole. Fig. 4 shows the disposition of the details of the receiver and the driving mechanism of the various parts thereof. Mechanism for changing the kind 30 of alphabet in use is shown in detail in Figs. 5, 6, 7, 8, 9 and 10. Fig. 11 shows a general view of a construction of apparatus for keeping the transmitter and receiver in synchronization. Fig. 12 is a diagrammatic view 35 of a friction clutch.

Referring now to Figs. 1 and 2 of the drawings, the transmitter is composed substantially of a horizontal cylinder composed of ten cylindrical disks 15, 16, 17, 18 and 19 40 of equal diameters and insulated from one another by thin washers. Brushes 15', 16', 17', 18', 19' of metal or carbon bear upon and beneath each of these cylindrical disks, and eighteen brushes 15'', 16'', 17'', 18'', 45 19'' bear on the cylinders. Nine of these cylindrical disks 16, 17, 18 and 19 are of the same width and the tenth 15, is nine times broader than the others. The eighteen brushes are equal and equally spaced. Nine 50 of them 15'' rest on the wide cylindrical disk 15. The perforated band or tape which is preferably formed by a machine of the kind set out in my pending application No. 666915, filed on the 20th December 1911, 55 is guided by parallel rollers and drawn forward as described in that application by two pressure rollers operated by the cylinder with which they are connected by a belt or by gear wheels. It thus passes between the 60 cylinder and the upper brushes. Two of these cylindrical disks (16) are intended for determining the direction of the current. They are arranged at the two ends of the cylinder. Five disks 17 are intended for 65 inserting a suitable resistance into the line

circuit. They therefore act to determine the strength of the line current. The broader disk 15 is intended to determine the voltage of the current. One of the narrower disks 18 as will hereinafter be seen has the function of changing the alphabets, and the remaining one 19 acts to keep the transmitter and receiver in synchronism. Two batteries of secondary cells P, N positive and negative respectively, serve as sources of electrical supply. The battery P has its positive pole connected with the upper brush resting on the disk 16. The brush 16' bearing on the underneath of this disk is connected to earth or to an insulated return. The negative battery is connected in the same way. The battery P is shown as divided into nine groups, each of the nine negative terminals being connected with one of the brushes 15'' resting on the top of the broader disk 15. The nine positive terminals of the battery N are connected with the same brushes and in the same order. Beneath the disk 15 a single brush 15' bears. It is electrically connected with the five brushes 17' bearing upon the underneath portion of the five disks 17 for determining the strength of the line current. A resistance r (see particularly Fig. 2) calculated in terms of the voltages employed and the maximum resistance of the line is employed to vary the current by half milliamperes, and is inserted between each of these brushes 17' as shown in Fig. 1.

The five brushes 17'' bearing on the upper surface of the five disks 17 are connected together and also to the brushes 18' and 19', which bear respectively on the upper surface of the disk 18 for changing the alphabet and the disk 19 for synchronizing. All of them are connected to the line L. The two disks 18 and 19 are also connected by the brushes 19'', 18'' to the extreme positive terminal of the negative battery, and to the extreme negative terminal of the positive battery respectively. When this arrangement is in operation the strip perforated in the manner set out in my application, Serial No. 666915, referred to above, is caused to pass under tension along the cylindrical face of the cylinder beneath the whole of the upper brushes 15'' to 19''. Of the three holes perforated the first places one of the cylinders 16 and consequently the corresponding battery into circuit in order to determine the direction of current, while the other cylinder 16 remains insulated by the tape. The second perforation places the potential cylinder 15 into circuit, connecting to it a brush corresponding to a given electromotive force and the third perforation allows the current to pass to the line L after having passed by way of one of the cylinders 17 through the additional selected resistance r . To sum up, in the case of positive direction of current for example, 130

the current passes from a given negative terminal to the potential cylinder 15 through the lower brush 15', through the contact brushes 17', the selected additional resistances r and passes out through the disk 17, brush 17'', and so into the line. It returns from the receiver either by means of an earth connection or through a return conductor and then through the brush 16', disk 16 and brush 16''. The current which is sent out by the synchronizing key is the greatest current in one of the two directions and therefore only requires two perforations for its transmission, that is one perforation to decide the direction of the current and the other for transmitting maximum voltage because no additional resistance is needed. The current sent out by the alphabet changing key is a similar current in the opposite direction.

Referring now more particularly to Fig. 3 in which a receiver of the improved system is shown which may be considered as totally free from self-induction, this it is well known is a necessary condition for rapid transmission. Essentially there is a convergent lens or photographic objective L, also a screen E at right-angles to the axis of this lens. The normal image of an illuminated element A B of this screen appears at a, b. However if a plain mirror m be arranged parallel to the axis of the lens L in the course of the pencil rays from A, B, the image of the latter is reflected to a', b', instead of being shown at a, b. This image a', b', may be arranged to be upon the axis of the lens L, upon the opposite side to the screen E. Also the mirror m may be arranged so that the center of the image a', b' lies at the optical center of the lens L. Also the mirror may be arranged so that the image of the element A, C, next to the element A, B, coincides with the image a', b'. In order to carry this out the rays from A, C are reflected by the mirror m' parallel with the mirror m and placed behind it in such a manner that the incident pencil of rays and the reflected pencil just touch the edges of said mirror without encountering it. The receiver as a whole is composed of a very dead-beat galvanometer G such as for instance is employed in Blondel's oscillograph, and a powerful and constant source of light F throwing an image of a square aperture upon the mirror H of the oscillograph. The oscillograph mirror H is adapted to illuminate the screen E, and if the oscillograph is of the kind in which there is a slight separation of the coils the pencil of rays reflected by its mirror H may be suitably reflected by the series of mirrors M, M², thus spreading the pencil of rays in order to illuminate the whole screen. The opaque screen E carries along a horizontal line, letters, figures and signs of the alpha-

bet. These characters are cut out in the screen and backed with a suitable ground glass K.

The photographic lens L and the small mirrors m, m', m² and m³ are arranged as above described. As a consequence all the signs of the alphabet tend to form their image at the optical center of the lens L as above set out. The adjustment of the mirrors although there is a large number of them, is comparatively simple because they are all parallel. Their vertical axes are all on the same straight line and the images of the characters are not absolutely contiguous owing to the spacing on the screen, so that by the resulting position of the incident and reflected rays, the size of the mirrors may be approximated so as not to interfere with each other. However in that case the aberration due to refraction must be corrected and the adjustment of the mirrors is very simple as above described in spite of their large number, and once adjusted they need never get out of correct position except in case of accident.

The receiving apparatus operates as follows: A definite current is transmitted from the line to the leads p of the oscillograph, and the mirror H of the latter is deflected according to the direction and strength of the current and so illuminates the desired character on the screen. Hence at that instant the image of that character only is formed at the optical center of the lens L, and this image is as sharp as that produced in any ordinary photographic apparatus. At this point O the photographic surface for recording the message transmitted is arranged. It should be pointed out that the letters on the screen E must be reversed in two senses, that is to say they must be upside down and run from right to left so that the photographic objective L, U may correct them. The movement of the photographic paper or film requires special mechanism for when setting up a newspaper the characters must be printed in lines one below the other to form columns. For this a horizontal movement is first required followed by a vertical movement and then a fresh horizontal movement in the same direction as the first and so on. In a teletype machine the band of paper R of sensitive film is of the same width as the column of the newspaper to be printed. It remains stationary during the printing of each line, the images of consecutive characters being caused to follow one another and to be placed side by side by means of the rotated and oscillated mirror S. An oscillated mirror is illustrated in Fig. 4, its movement being governed by the rotation of a cam T of spiral form. When it is released it allows its sudden return to the original position. It must however be observed that the

- 4
- reflected image will be on a cylinder, the axis of which coincides with the axis of rotation of the mirror, and therefore the impression will not be clear because it is out of focus. In order to remedy this the focal length of the lens L and consequently the position of the image a' , b' is modified by the interposition of the divergent lens U which transfers the image a' , b' to a'' , b'' .
10. The mirror S is arranged in the path of this broadened pencil of rays.
- In order to correct the focusing on the strip R it is necessary to modify the position of the lens U in accordance with the angular position of the mirror S. The lens U must be nearest the mirror S when the latter is in its mid-position and farthest away in the two end positions. Fig. 4 illustrates a device for carrying this condition of affairs into effect. The lens U works in guides V, and its movements are controlled by a connecting rod Y connected with an eccentric Z mounted on the axis W, about which the mirror S turns. When a line of newspaper is printed the sensitive band R is shifted from the space of one line along its axis and a fresh line is printed below the previous one. The displacement of the mirror S and the band R may be carried out by means of an electric motor 50. The two movements may be made independent. For example the spindle 54 of the roller 51 over which the band R passes may be geared to the motor 50 driving the mirror S so that on a complete rotation of the latter the band R may be moved forward one tooth. The sensitive film or photographic paper R is wound on a reel 51 and in order to be printed it moves past a longitudinal window 53 of the same height as the characters and the same length as a line of a column, and then the paper is passed through a dish 52 of slightly oxidizable developer such as metol. When it is desired to change the alphabet the mechanism shown in Figs. 5 to 10 is employed. As the ninety characters capable of being transmitted without change of alphabet are all placed in a single line the opaque screen E may for the sake of convenience be made as a cylindrical surface and several alphabets may be arranged parallel to one another thereon in the direction of generating lines of this surface. This cylinder is controlled upon the principle that the jerks or jolts produced by the electromagnet 20 actuated by the current sent by the alphabet key and by the disks 18, and brushes 18', 18'' in the transmitter act upon a ratchet 21 in the same direction always and produce in every revolution of this ratchet a complete oscillation backward and forward of the screen E. Thus each actuation of the electromagnet places in line the generating line of the next alphabet. If therefore we start with the alphabet I and

there are seven of them it will require six actuations to cause the alphabets II, III, IV, V, VI and VII to defile past seeing that the six following actuations (the ratchet has twelve teeth) return them to their original position by causing them to pass in the order VI, V, IV, III, II, I. Suitable gearing is provided for bringing about this movement. Two wheels 24, 25, toothed over a half of their circumference, and of such a diameter that this half circumference has the same length as the toothed sector turning the alphabet cylinder through an angle corresponding to the oscillation, are keyed upon the shaft 22 of the ratchet. The first 70 of these wheels 24 engages with a toothed sector 26 mounted on the spindle 23 of the cylinder E. The other wheel 25 engages with a wheel 27 which is itself in engagement with a second toothed sector 28 on the 80 spindle 23. The smooth portions α , γ , β , α' , γ' , β' of the circumference of the wheels 24, 25 must allow the teeth of the sector 26, and of the actuated wheel 27 to pass.

In Fig. 5 is shown an arrangement for the operation of the sector 26 of the cylinder. Fig. 6 shows the arrangement of the two sectors 26, 28 and the intermediate wheel 27 in end view. Fig. 7 is an edge view of the two wheels 24 and 25, the one being directly engaged with the sector 26, and the other being disengaged from the sector 28 and engaged with the wheel 27. In Fig. 8 the alphabet I is in a position for use. When the toothed arc α , δ , β turns in the direction shown by the arrow the alphabets II, III, IV, V, VI, VII will take the place of alphabet I in order. As seen in Fig. 9 the alphabet VII is in position for use and the wheel 24 has just become disengaged from the sector 26, the wheel 25 entering into engagement with 27 and turns in the direction shown by the arrow in order to cause the alphabets VI, V, IV, III, II, I to take the place of alphabet VII in order. The ratchet 21 must have a number of teeth equal to twice the number of the alphabets less two (for seven alphabets there are twelve teeth). 105

The system just described has the advantage that the alphabet screen E is given regular displacements but in a simplified modification the arrangement shown in Fig. 10 may be employed.

The connection between the ratchet 21 120 and the screen E may be made by means of a connecting rod and a crank on the spindle 22. Then if the ratchet wheel has equal teeth the connecting rod will push the screen upward and cause it to descend in 125 definite steps. The alphabets on the screen must be placed in lines which will be in a proper relative position to the lens of the receiver after each of these steps. The spaces on the screen may be made equal if 130

the teeth of the ratchet wheel 21 are suitably cut, or the ratchet wheel may be replaced by a cam of suitable contour. In order to make this operation more clear assume the following example: The matter composed passes from the alphabet II to the alphabet VI. For this the compositor operates the alphabet key four times in succession. The perforator makes four successive holes in the tape and then in its turn the transmitter sends four impulses of maximum current in one direction which act four times on the electromagnet and turn the ratchet 21 by four teeth. The alphabet cylinder therefore advances four stages, the alphabet VI taking the place of the alphabet II. Or again assuming that the matter composed has to pass from the alphabet III to the alphabet II. To obtain this the compositor operates the alphabet key nine times in succession. The perforator makes nine holes and as before the ratchet turns the cylinder through nine stages. After the fourth movement however, the toothed arc which is acting releases one of the two wheels 26, 28 and the other is engaged. The last five movements of the ratchet cause the alphabet cylinder to turn backward so that the alphabet VII is replaced in turn by the alphabets VI, V, IV, III, II. In this arrangement there are no complicated mechanical parts capable of being put out of order such as cams, springs and the like, and it has the further advantage of preventing composers' errors. The compositor need only know that for any change of alphabet he must make as many contacts as are necessary for passing to the maximum number of alphabets, and then pass down to the one he desires. In the second of the above two examples he need only count in order to go from three to two, IV, V, VI, VII, VI, V, IV, III, II. This calculation may even be avoided by arranging on the keyboard as many special keys as there are alphabets and connecting them all electrically. It will then be sufficient to touch them all from the one previously used down to the last on the right and then to return similarly toward the left until the one corresponding to the fresh alphabet desired is reached.

With apparatus such as is above described an arrangement for synchronizing the receiver and transmitter is evidently not indispensable because the only effect of differences in speed between the transmitter and receiver would be to separate out or close together the characters from one another, but preferably this disadvantage is avoided and it assists in preventing the addition of errors. For this purpose the motor 50 driving the rotating or oscillating mirror S and the film R is adjusted to travel slightly too fast. It drives these members by means of

a friction gear 55 and 56 so as not to be pulled up if these parts are momentarily locked. A disk 30 with a cam 31 is fixed upon the shaft 29 which drives the friction gear and against this disk 30 the hooked extremity 32 of the armature 33 of an electro-magnet 39 bears. This electro-magnet is controlled by a relay 34 in series with the line and adjusted so as only to act under a current of the maximum strength used for synchronizing. For this purpose the synchronizing key on the perforator makes a special perforation so that the brush 19 transmits the requisite strength of current. As the receiver has a tendency to run too fast the cam 31 of the disk 30 meets the hook 32 of the armature and the system is stopped while the motor continues to revolve. At this moment however, the synchronizing current is sent to line. The relay 34 acts to close the circuit of the electro-magnet 39, its armature 33 is attracted, the cam 32 is released and the system resumes its course until it is stopped again. The whole arrangement is of course carried out so that the correcting shaft only makes one revolution between two transmissions of the synchronizing current. A suitable form of friction clutch is shown in Fig. 12. It consists of two plates 35 and 36 with or without an india-rubber plate arranged between them. The driven plate 36 is forced against the driving plate 35 by elastic rings 37 adjusted by tightening up the nut 38. The more the nut is tightened up the more the rings are compressed.

The typographic form is made by photogravure. The film which is rendered negative by way of counter-type, as hereinbefore described, is applied to strips of zinc slightly larger than a column of a newspaper and rendered sensitive by an ordinary process, such as the so-called "bitumen" process. This band of zinc is insulated and then engraved. The various bands are dressed in the etching machine and placed together after having been separated by strings. The matrix is then formed by treating the sheets thus formed like ordinary compositions. As the perforated band is formed at the same time as the composition, and as the photographic impression of the characters is the interpretation of the perforated band, it is evident that the result will be the exact reproduction of the original composition. The following conditions must however be observed: The alphabets cut out on the screen of the receiver must have the same characteristics as the matrices contained in the magazines of the original or transmitting composition machine. Also, when a blank space, an interlining space or an interval to be reserved, is met with in the text, the compositor must suitably displace the perforated tape by directly actu-

ating the electromagnet for displacing the perforator by the special key. This movement is in fact the same as that which insures the displacement of the cylinder in 5 typewriting machines. When a large space is to be reserved for an illustration, the compositor has only to transmit a conventional word and indicate the number of lines to be reserved. The setter-up at the receiving 10 station then knows that he must cut out his zinc at this place and what size of space he must reserve.

All the foregoing considerations apply in 15 a similar manner to the arrangement of a telegraph apparatus for the ordinary requirements of transmission of telegrams. But the rate of working may then be considerable seeing that the transmission is 20 done automatically and with a single emission of current per character.

The arrangement of the electric perforator enables the tape to be perforated when writing the text of the telegram with a typewriting machine resembling in all 25 points an ordinary machine, the keys of which when depressed also close the necessary electric contacts as set out in the pending application hereinbefore referred to. This arrangement has several important 30 advantages of which the following are the chief:—1. Any one can himself make his transmission tape without tools or supplementary work. 2. The text may be corrected and this correction is performed by the 35 normal working of the typewriting machine when the keys are depressed. 3. This justification or correction which is handed in at the telegraph office window at the same time as the tape, may have been previously applied to the copy of the letter. 4. From the point of view of the charge, seeing that all the characters correspond to the same linear displacement of the perforated band, the charge may be logically 40 made according to the length of the tape, that is to say, to the number of letters. For this reason and in order to facilitate reading, the tapes may be divided and subdivided, each division thus representing a 45 unit of the charge. The width of the tape must evidently be agreed upon and the State might even reserve the sale to itself. Under these conditions customers have only 50 to hand in their band at the telegraph office window. The employee, for whom no special competency is necessary, will only have to cause the band to enter the transmitter which is always in motion. It emerges of 55 itself, immediately the message is transmitted and may be retained. The first effect of the despatch of a telegram at the receiver is to start the motor 50 by the energizing of the electro-magnet 58 (Fig. 4) and thereby the release of an automatic 60 switch such as diagrammatically illustrated

at Fig. 4 and the telegram is received photographed in roman characters on a tape resembling in all points the tapes at present in use for telegrams.

The tachytelegraph is simpler in construction than the teletype machine in a number of ways. For example in the tachytelegraph it is no longer necessary to provide for change of alphabet nor for synchronizing. Hence two disks of the transmitter cylinder are dispensed with, also two of the electromagnets of the perforator and also as well all the parts in connection with these functions at the receiving station. Lack of synchronizing only has the effect 75 of a variation in the respective spacing of two letters on the telegraphic tape. However the perforations for synchronizing and for change of alphabet must be absent if the charge is levied by unit of length of 80 tape. Also as the impression takes place at the receiver on an endless tape and no longer in columns, the revolving mirror is no longer required. The motor has only to cause the sensitive band to move forward 85 in a continuous and uniform manner by actuating two pressure rollers. All the letters form their image at the same place on the principal axis. Further the printing 90 may be done positively on very sensitive paper. As telegraphic messages do not require ninety characters, the number of parts of the perforator and transmitter may be simplified. By having recourse, for instance, as in the Baudot machine to 95 thirty-two signs it will suffice to have four potential brushes and four intensity disks. Sixteen different strengths of current in 100 each direction or thirty-two in all, are thus obtained. Under these conditions the transmitter only comprises ten brushes instead of eighteen and seven disks instead of ten. The width of the band may also be proportionately diminished. At the receiving 105 station sixteen mirrors are sufficient on each side of the principal axis. Finally the contiguous values of the strength of current employed may be more widely separated and it is then easy to arrange a difference 110 of 1 to 1.2 milliamperes between two adjacent values of the current. By taking ± 10 milliamperes as the initial value for 1.2 milliamperes difference, the current varies 115 between $+10$ and $+29.2$ milliamperes in one direction and between -10 and -29.2 in the other direction.

I declare that what I claim is:—

1. In a transmitter for a tachytelegraph or teletype machine, the combination of a 120 perforated band punctured with sets of three perforations, the perforations of each set being arranged in the same straight line at right-angles to the edge of the band, a source of current and electrical means controlled by the perforated band for control- 125 130

- ling the direction, voltage and strength of the current impulses.
2. In a transmitter for a tachytelegraph or teletype machine, the combination of a perforated band punctured with sets of three perforations all of equal size, the perforations of each set being arranged in the same straight line at right-angles to the edge of the band, a plurality of concentric 50 conducting cylinders of equal diameter arranged with their end surfaces parallel but insulated from each other and adapted to allow the perforated band to pass over a generating line thereof, a plurality of brushes resting on the said band and adapted to make contact with their underlying cylinders through the perforations in the said band, a line, a source of electric supply connected thereto, and electrical connections 55 from the line and from the source of electric supply to the said brushes and to and between the said cylinders to enable the perforated band to control the direction, voltage and strength of the current impulses.
- 25 3. In a transmitter for a tachytelegraph or teletype machine, the combination of a perforated band punctured with sets of three perforations all of equal size, the perforations of each set being arranged in the same straight line at right-angles to the edge of the band, a plurality of concentric 60 conducting cylinders of equal diameter arranged with their end surfaces parallel but insulated from each other and adapted to allow the perforated band to pass over a generating line thereof, a plurality of brushes resting on the said band and adapted to make contact with their underlying cylinders through the perforations in the said band, a line, a resistance in series therewith, two sources of electricity having two pairs of the brushes connected with the positive and negative terminals thereof, and having a series of the brushes connected to 65 the successive elements of both the said sources of electricity, a series of the brushes being also connected to the line for varying the line resistance, electrical connections to said cylinders and resistant connections between said cylinders to enable the perforated band to control the direction, voltage and strength of the current impulses.
- 45 4. In a tachytelegraph or teletype machine the combination of a line, a source for supplying current thereto, a perforated band for controlling the direction, voltage and strength of the current impulses, an oscillograph for receiving the said impulses from the line, a screen bearing characters 70 adapted to be illuminated one by one by the mirror of said oscillograph, and means for photographically recording the characters so illuminated.
- 55 5. In a tachytelegraph or teletype machine, the combination of a transmitter, a

perforated band adapted to control the direction, voltage and strength of the current impulses sent by the transmitter, an oscillograph for receiving the current impulses from the transmitter, a screen containing all 75 the characters to be transmitted and illuminated one by one by the mirror of said oscillograph, a series of lenses and mirrors arranged to form an image of any character illuminated at a fixed point and a photographic surface passing through said point and adapted to receive an impression of said image.

6. In a teletype machine the combination of a transmitter, a perforated band 80 adapted to control the direction, voltage and strength of the current impulses sent by the transmitter, a screen bearing the characters to be transmitted, electrical means controlled by said current impulses for illuminating said characters, a series of lenses and mirrors arranged to form an image of any character illuminated at a fixed point, a photographic surface passing through said point and adapted to receive an impression 85 of said image, and an oscillating mirror for throwing the successive images of the characters to be printed in lines running transversely across said surface.

7. In a teletype machine the combination 90 of a transmitter, a perforated band adapted to control the direction, voltage and strength of the current impulses sent by the transmitter, a screen bearing the characters to be transmitted, electrically operated means for illuminating said characters, a series of lenses and mirrors arranged to form an image of any character illuminated at a fixed point, a photographic surface passing 95 through said point and adapted to receive an impression of said image, an oscillating mirror adapted to throw said image on to the photographic surface, and a helical cam adapted to turn said oscillating mirror 100 slowly in one direction and then instantaneously in the other direction.

8. In a receiver for a teletype machine, the combination of an oscillograph, a cylindrical screen, a series of alphabets of characters on the screen arranged along generating lines of the cylinder, means operated by the said oscillograph for illuminating the character transmitted, and means for rotating the cylinder in order to bring one or other of the alphabets arranged thereon into 110 the operative position.

9. In a receiver for a teletype machine, the combination of an oscillograph, a screen bearing the characters to be transmitted and illuminated by means of the mirror of said oscillograph, a series of alphabets arranged on the said screen and a system of wheels with partially toothed sectors for turning and returning the screen.

10. A tachytelegraph or teletype machine 120

comprising in combination a perforated band formed with sets of three perforations, the perforations of each set being arranged in the same straight line at right-angles to the edge of the band, a line, a source of electrical supply thereto and electrical means controlled by the perforated band for controlling the direction, voltage and strength of the current impulses in the line, an oscillograph for receiving the said impulses from the line, a screen bearing characters adapted to be illuminated one by one by means of said oscillograph, and means for photographically recording the character so illuminated.

11. A tachytelegraph or teletype machine comprising in combination a perforated band formed with sets of three perforations all of equal size, the perforations of each set being arranged in the same straight line at right-angles to the edge of the band, a plurality of concentric conducting cylinders of equal diameter arranged with their end surfaces parallel but insulated from each other, and adapted to allow the perforated band to pass over a generating line thereof, a series of brushes resting on the said band and adapted to make contact with their underlying cylinders through the perforations in the said band, a line, a source of electric supply connected thereto, and electrical connections from the line and from the source of electric supply to the said brushes, and to and between the said cylinders to enable the perforated band to control the direction, voltage and strength of the current impulses, an oscillograph for receiving the current impulses from the line, a screen bearing all the characters to be transmitted adapted to be illuminated by the oscillograph, a series of lenses and mirrors arranged to form an image of any character illuminated at a fixed point and a photographic surface adapted to receive an impression of said image.

12. A teletype machine comprising in combination a transmitter, a perforated band adapted to control the direction, voltage and strength of current impulses sent by the transmitter, an oscillograph for receiving the said impulses from the transmitter, a cylindrical screen, a series of alphabets of characters on the screen arranged along generating lines of the cylinder, and adapted to be illuminated by said oscillograph, and means for rotating the cylinder in order to bring one or other of the alphabets arranged thereon into the operative position.

13. A teletype machine comprising in combination a perforated band formed with sets of three perforations all of equal size, the perforations of each set being arranged in the same straight line at right-angles to the edge of the band, a plurality of concentric

conducting cylinders of equal diameter arranged with their end surfaces parallel but insulated from each other and allowing the perforated band to pass axially over its surface, a series of brushes resting on the said band and adapted to make contact with their underlying cylinders through the perforations in the said band, two sources of electricity having two pairs of the brushes connected with the positive and negative terminals thereof and having a series of the brushes connected to the successive elements of both the said sources of electricity, a series of the brushes being also connected to the line for varying the line resistance, electrical connections to said cylinders and resistive connections between said cylinders to enable the perforated band to control the direction, voltage and strength of the current impulses, a screen bearing the characters to be transmitted, electrical means controlled by the said current impulses for illuminating said characters, a series of lenses and mirrors arranged to form the image of any character illuminated at a fixed point, a photographic surface adapted to receive an impression of said image and an oscillating mirror for throwing the successive images of the characters to be printed in lines running transversely across said surface.

14. In a teletype machine, the combination of a perforated band formed with sets of three perforations, the perforations of each set being arranged in the same straight line at right-angles to the edge of the band, a source of electrical supply, electrical means controlled by the perforated band for controlling the direction, voltage and strength of current impulses given out from said supply, an oscillograph adapted to receive said impulses, a cylindrical screen, a series of characters on the screen arranged along generating lines of the cylinder, and adapted to be illuminated by the oscillograph, and means for rotating the screen in order to bring one or other of the alphabets arranged thereon into operative position.

15. A method of transmitting signals for tachytelegraph or teletype systems which consists in selecting any one of a plurality of sources of electric current, each having a different predetermined voltage and differing from one another both as regards magnitude and direction, connecting such source of current across the line in circuit with a resistance of selected value, and choosing the voltages and resistances so that every selection sends a different definite value of current to the line corresponding to the signal to be transmitted.

16. A tachytelegraph or teletype system comprising a line, a transmitting station including a plurality of sources of electric current each having a different predeter-

- mined voltage varying both as regards magnitude or direction, a plurality of resistances of predetermined value and a contact making device adapted to select one of said 5 sources of electric current, and to select resistance of predetermined value and connect these in circuit with the line, and a receiving station having a responsive device adapted to be actuated differently for each 10 predetermined value of current sent through the line by which the signal may be detected, the voltages and resistances of the transmitting station being so chosen that every selection sends a definite value of current 15 to the line corresponding to the signal to be transmitted.
17. In a tachytelegraph or teletype machine, a transmitter including a plurality of 20 sources of electric current each having a different predetermined voltage varying both as regards magnitude or direction, a plurality of resistances of predetermined value and a contact making device adapted to select one of said sources of electric current and a resistance of predetermined 25 value and connect these in circuit with the line, the voltages and resistances of the transmitting station being so chosen that every selection sends a definite value of current
- rent to the line corresponding to the signal 30 to be transmitted.
18. In a tachytelegraph or teletype machine, a plurality of sources of electric current, each having a different predetermined voltage both as regards magnitude and direction, a plurality of resistances of predetermined value in circuit with the line, a receiver comprising a responsive device connected to the line and adapted to be actuated differently for every combination of a 35 plurality of sources of electric current each having a different predetermined voltage both as regards magnitude and direction and of the plurality of resistances of predetermined value placed in circuit with the 40 line, a member provided with a plurality of distinct characteristics and means adapted to cause the co-action of said responsive device with said member at positions having characteristics corresponding to the signals 45 transmitted.
- In witness whereof, I have hereunto signed my name this 12th day of May, 1911, in the presence of two subscribing witnesses.
- EDOUARD BELIN.
